UNITED STATES PATENT OFFICE.

CHARLES C. PIERCE, OF NACOGDOCHES, TEXAS.

PROSTATE APPLICATOR.

Application filed March 29, 1926. Serial No. 98,253.

This invention relates to prostate applicators, and has more particular reference to a means whereby infected prostatic glands may be treated by hot or cold applications without the media being used actually coming in contact with said glands.

The invention further aims to provide an applicator of this character that may be easily and without pain inserted into the body, and that after insertion may have a continuous supply of hot or cold water passing therethrough without the fluid actually coming into contact with the parts being treated.

Other objects will become apparent as the nature of the invention is better understood, the same comprising the novel form, combination and arrangement of parts hereinafter more fully described, shown in the accompanying drawing and claimed.

In the drawing:—

The figure is a longitudinal section of an applicator constructed in accordance with the present invention.

Now having particular reference to the drawing, my prostate applicator constitutes the provision of a relatively short tube 5, preferably of fibre or hard rubber or metal that is externally threaded at its forward end for receiving the open internally threaded end of an elongated bulbous shaped head 6 that is pointed at its forward end for facilitating the easy insertion of the same into the affected part, the outer end of the tube 5 being formed with a rounded enlargement or head 7 to act as a closure when inserted.

The outer end of the tube 5 is internally threaded for receiving the threaded end of a Y-pipe 8, the legs 9 and 10 of which are adapted to have arranged thereover at their outer ends flexible pipes (not shown), the pipe attached to the leg 9 being in communication with a source of fluid supply while the fluid that is discharged into the head in the manner hereinafter described, is adapted to discharge through the pipe attached to the leg 10.

Formed integrally with the discharge end of the leg 9 of the Y-pipe 8 is an elongated tube 11 that extends through the tube 5 and

into the head 6, the portion thereof within said head being formed with openings 12 in order to permit the fluid to discharge into the head for heating the same which heat will be transmitted to the glands being treated. Obviously as the fluid discharges from the tube, the same will pass rearwardly and discharge from the applicator in the manner as previously described.

The advantages of an applicator of this character will be appreciated by those skilled in the medical art, and even though I have herein shown and described the device as consisting of certain detail structural elements it is nevertheless to be understood that minor changes may be made therein without affecting the spirit and scope of the appended claim.

Having thus described the invention, what I claim as new and desire to secure by Letters Patent is:—

As a new article of manufacture, a rectal applicator for use in association with prostatic glands, a body including a Y-joint composed of hollow converging branches merging into a screw threaded neck having an outstanding flange, an apertured fluid supply tube connected with one of said branches at the juncture of said branches, and extending through and beyond said coupling neck, a comparatively short outer tube surrounding said supply tube, said outer tube being composed of heat insulation material, being provided with a screw threaded socket at one end receiving said neck and abutting said flange, being provided at said same end with an enlargement providing a stop shoulder, being provided at its opposite end with external screw threads, said supply tube extending through and beyond the screw threaded end of the outer tube, and a hollow metallic head of bulbous form connected to the screw threaded end of said outer tube and surrounding said inner supply tube, said head being connected with the screw threaded end of said outer tube and being of elongated ovate configuration.

In testimony whereof I affix my signature.

CHARLES C. PIERCE.
